FOOD TRAY

Oliver R. St. Andre, Chicopee, Mass., assignor to David L. Sokol, Springfield, Mass.

Filed Nov. 6, 1972, Ser. No. 304,122

Term of patent 14 years

Int. Cl. D7—99

U.S. Cl. D7—35

FIG. 1

FIG. 2

FIG. 1 is a top plan view of a food tray showing my new design;

FIG. 2 is a side elevation view of the food tray of FIG. 1;

FIG. 3 is a bottom plan view of the food tray of FIG. 1; and

FIG. 4 is a side elevation view taken along the line 4—4 of FIG. 3.

I claim:

The ornamental design for a food tray, as shown and described.
